SULFONIC ESTER ANALOGUES OF
NITROGEN MUSTARDS

James M. Sprague, Drexel Hill, and Edward L. Engelhardt, Collingdale, Pa., assignors to Merck & Co., Inc., a corporation of New Jersey

No Drawing. Application May 1, 1951,
Serial No. 224,072

9 Claims. (Cl. 260—456)

1

This invention relates to new sulfonic ester analogs of nitrogen mustards, and more particularly to compounds having the following general structural formula:

In this compound R is selected from alkyl radicals having up to 10 carbon atoms, aralkyl radicals having up to 10 carbon atoms, cycloalkyl radicals selected from cyclopentyl and cyclohexyl, and the radical $-\text{CH}_2\text{CH}_2\text{X}$. The alkyl radical can be a straight or branched chain and can include a terminal saturated ring. The radical R can also include, for example, alkoxy groups, halogen groups, ether linkages, at least two carbons removed from the nitrogen. R can not be hydrogen.

In the known compounds of this type, X is a halogen such as chlorine. Representative compounds, when X is a halogen and R is as above, set forth, are illustrated in the article, "Chemical Reactions of the Nitrogen Mustard Gases" in eight sections, by Max Bergmann and others, in the September 1946 issue of The Journal of Organic Chemistry, vol. 11, Number 5, pages 518 to 591 inclusive.

When the free base is dissolved in a polar solvent, the compound undergoes an internal cyclization to form the following ions:

It will be noted that only one ethylenimmonium ring is formed in the initial cyclization. When this ring is opened by hydrolysis or by the addition of an anionic reagent, the other 2-haloalkyl groups may cyclize in the same manner.

To determine the rate at which cyclization occurs, the rate of formation of the cyclized ion is measured by the rate of reaction of the compounds of general structures (1) with sodium thiosulfate. This reaction appears to take place according to the following sequence:

The rate of cyclization is the rate determining step of the overall reaction. To determine the relative rates of formation of the cyclized ion, therefore, it is merely necessary to add the com-

2

ound to a solution containing sodium thiosulfate and to measure the rate of decrease of the sodium thiosulfate concentration. For example, tests show that to react one mole of 2,2'-dichloro-N-methyl-diethylamine with 1.8 mole of thiosulfate, more than 35 minutes is required.

In the case of the known compounds in which X is a halogen such as chlorine, the rate of this cyclization is therefore quite slow. In accordance with the present invention, it has been discovered that if the X radical of the compound is a sulfonic ester radical, the rate of cyclization is very unexpectedly increased, and in most instances is too rapid to be measured readily at room temperature.

This rapid rate of cyclization of the compounds of the invention is of particular importance when the material is used as a therapeutic agent. The compounds of the invention exhibit viricidal activity and some of them show radiomimetic activity.

The reason for the extremely rapid cyclization of the compounds of the invention is not understood. It would be expected that such a marked difference as is observed would not occur merely by the substitution for the halogen radical of a sulfonic acid ester radical.

The compounds of the invention, that is, those in which X is a sulfonic acid ester, may therefore be represented by the formula:

35. The R' substituent may be any lower alkyl radical up to eight carbon atoms and it may be either straight or branched chain. Or R' may be aryl or aralkyl such as phenyl, p-tolyl or benzyl, or aryloxyalkyl such as phenoxyethyl. Representatives of these organic radicals will be apparent from the subsequent examples.

The substituent R of the compounds of the invention may be selected from the class defined above, and more specifically, illustrated in the aforementioned article by Bergmann and others. The exact character of R is not critical in the present invention within this class of radicals, inasmuch as the invention is primarily concerned with the sulfonic acid ester character of the substituent X. It may be observed that an ethylene radical is present between the ester oxygen and nitrogen constituents of the compound. Either of these two carbons may bear, instead of hydrogen atoms, substituents such as lower alkyl radicals without materially impairing the desired

cyclization or the intended results of the invention.

To obtain the compounds of the invention it is possible to follow several different procedures. For example, the hydro-chloride of a 2,2'-di-chloro-N-substituted diethylamine may be treated with the silver salt of the selected sulfonic acid according to the following scheme:

In practice the reactants are dissolved in a polar non-hydroxylic solvent such as a lower alkyl cyanide, for example, methyl cyanide. The mixture should be heated for a period from 3 to 6 hours at a temperature of from 60° to 100° C. At the end of this time the mixture is cooled and the precipitated silver chloride separated. The sulfonic acid ester of the 2-dialkylaminoethanol is recovered in the form of its sulfonic acid salt by evaporating the solvent.

Another method by which the products of the invention may be obtained is by treating the 2,2'-dihydroxy-N-substituted diethylamine with the anhydride of the selected sulfonic acid, as illustrated by the following:

In carrying out this reaction the ingredients may be mixed together in the presence of a solvent such as benzene, chloroform, or ether and the mixture allowed to stand at room temperature for a period of 3 to 15 hours, or the solution may be heated to refluxing for an hour. The desired sulfonic acid ester is obtained in the form of its sulfonic acid salt by evaporating the solvent.

Somewhat higher yields are obtained if the 2,2'-dihydroxy-N-substituted-diethylamine is treated with the alkanesulfonic anhydride in the presence of a lower alkyl cyanide such as methyl cyanide as a solvent. This reaction may be carried out at reflux temperature for 1 to 7 hours. To recover the desired product, the isolation procedure mentioned above may be carried out.

The invention will be further illustrated by reference to the following examples:

Example 1.—2,2'-dihydroxy-N-methyldiethylamine, 7.27 g. (0.0610 mole) was dissolved in 25 ml. of dry acetonitrile. The solution was added dropwise to a solution of 23.28 g. (0.134 mole) of methanesulfonic anhydride in 65 ml. of dry acetonitrile while stirring and maintaining the reaction mixture at room temperature. The solution was allowed to stand overnight at room temperature and the solvent then evaporated at 55-60° under reduced pressure. The syrup residue was dissolved in 68 ml. of a 4.43 N solution of dry hydrogen chloride in absolute alcohol, the solution diluted with 150 ml. of absolute ether and chilled. The crystalline product that separated was recrystallized from a mixture of methanol containing 1% of water and ether. The yield of white crystalline product, 2,2'-di-mesyloxy-N-methyldiethylamine hydrochloride, M. P. 112-113° was 13.47 g. (57%).

Example 2.—2,2',2'',trihydroxytriethylamine, 2.73 g. (0.0183 mole) dissolved in 10 ml. of dry acetonitrile was added dropwise to a solution of 11.0 g. (0.063 mole) of methanesulfonic anhydride in 25 ml. of dry acetonitrile while maintaining the reaction mixture at room temperature. After standing overnight at room temperature, the mixture was heated to refluxing for 1 hour. The solvent then was evaporated and the residue dried at 50-55° C. under reduced pressure. The viscous syrupy residue weighed 13.80 g. and contained 56% of the methanesulfonic acid salt of 2,2',2''-trimesyloxytriethylamine as estimated by titration against sodium thiosulfate. This corresponds to a yield of 88% of the theoretical.

Example 3.—2,2'-dichloro-N-cyclohexyldiethylamine hydrochloride, 2.61 g. (0.01 mole), dissolved in 70 ml. of hot acetonitrile was added dropwise to a solution of 8.37 g. (0.03 mole) of silver p-toluenesulfonate in 30 ml. of dry acetonitrile. The reaction mixture was refluxed with stirring for 6 hours. The precipitated silver chloride then was removed by filtration and the solvent evaporated at 40-50° under reduced pressure. The residue contained 79% of the p-toluenesulfonic acid salt of 2,2'-di-(p-tosyloxy)-N-cyclohexyldiethylamine as estimated by titration against sodium thiosulfate.

Example 4.—By substituting 6.09 g. (0.03 mole) of silver methanesulfonate for the silver p-toluenesulfonate of Example 3 and following the procedure of Example 3, except that the reaction mixture was refluxed for only 3 hours, a viscous yellow syrup containing 79% of the methanesulfonic acid salt of 2,2'-di-(mesyloxy)-N-cyclohexyldiethylamine was obtained.

Example 5.—The process of Example 4 was carried out but using an equimolecular amount of 2,2'-dichloro-N-butyldiethylamine hydrochloride instead of the corresponding cyclohexyl compound. The methanesulfonic acid salt of 2,2'-di-mesyloxy-N-butyldiethylamine was obtained.

Example 6.—The process of Example 4 was carried out but using an equimolecular amount of 2,2'-dichloro-N-octyldiethylamine hydrochloride instead of the corresponding cyclohexyl compound. The methanesulfonic acid salt of 2,2'-di-mesyloxy-N-octyldiethylamine was obtained.

Example 7.—2,2'-dihydroxy-N-(β -naphthyl)-diethylamine, 2.31 g. (0.01 mole) was dissolved in 60 ml. of dry acetonitrile. The solution was added dropwise with stirring to a warm solution of 6.53 g. (0.02 mole) of p-toluenesulfonic anhydride in 60 ml. of dry acetonitrile. The yellow-orange reaction mixture was refluxed for 6½ hours after the addition was complete, then allowed to stand overnight at room temperature. The solvent was evaporated and the residue dried to constant weight at 50-55° C. under reduced pressure. The residue then was dissolved in absolute acetone, the solution filtered, diluted with absolute ethanol and chilled. The crystalline product that separated was recrystallized from a mixture of absolute acetone and absolute ethanol to give 1.53 g. (28%) of 2,2'-di-(p-tosyloxy)-N-(β -naphthyl)-diethylamine, M. P. 113-114° C.

Example 8.—The process of Example 3 was carried out but using an equimolecular amount of silver benzenesulfonate instead of the silver p-toluenesulfonate. The compound obtained was the benzenesulfonic acid salt of 2,2'-di-benzenesulfonyloxy-N-cyclohexyldiethylamine.

Example 9.—The process of Example 3 was carried out but using an equimolecular amount

of silver α -toluenesulfonate instead of the silver p-toluenesulfonate. The compound obtained was the α -toluenesulfonic acid salt of 2,2'-di-(α -tosyloxy)-N-cyclohexyldiethylamine.

It has been pointed out above that tests show that to react 1 mole of 2,2'-dichloro-N-methyl-diethylamine with 1.8 mole of thiosulfate, more than 35 minutes is required at 25° C. The rapidity of the cyclization which occurs with compounds of the invention is shown by the fact that 2,2'-dimesyloxy-N-methyl-diethylamine reacts with 1.8 mole of thiosulfate in less than 5 minutes at 25° C.

Other examples of the invention will be apparent from a consideration of the compounds represented to be therapeutically effective in the above mentioned article by Bergmann and others, using those compounds as starting materials and carrying out the reactions of the above examples.

It will be noted that the product obtained from carrying out the reactions set forth above, is the salt of the same sulfonic acid which is involved in the ester linkage. It will be appreciated from what has been set forth above, that a primary feature of the invention resides in the sulfonic acid ester structure of the compound and that the acid that forms the salt of the compound is relatively unimportant. Thus, although the compounds obtained in the above examples have as the salt-forming acid the same acid that occurs in the ester, the invention contemplates salts of other acids such as the hydrochloric, sulfuric, and other sulfonic acids, as well as carboxylic acids. The free base can be prepared from this salt by neutralization with one equivalent of an alkali, but in most instances this free base is not stable.

What is claimed is:

1. Compounds having the formula:

in which R is selected from the group consisting of alkyl radicals having up to 10 carbon atoms, aralkyl radicals having up to 10 carbon atoms, cyclopentyl, cyclohexyl, $-\text{CH}_2\text{CH}_2$ halogen, and $-\text{CH}_2\text{CH}_2\text{OSO}_2\text{R}'$ radicals, and in which R' is selected from the class consisting of lower alkyl, phenyl, tolyl and benzyl radicals.

2. Compounds having the formula:

in which R is selected from the group consisting of alkyl radicals having up to 10 carbon atoms,

55

Bergmann, Journal of Organic Chemistry, vol. 11, p. 518 (1946).

aralkyl radicals having up to 10 carbon atoms, cyclopentyl, cyclohexyl, $-\text{CH}_2\text{CH}_2$ halogen, and $-\text{CH}_2\text{CH}_2\text{OSO}_2\text{R}'$ radicals, and in which R' is selected from the class consisting of lower alkyl radicals.

3. Compounds having the formula:

in which R is selected from the group consisting of alkyl radicals having up to 10 carbon atoms, aralkyl radicals having up to 10 carbon atoms, cyclopentyl, cyclohexyl, $-\text{CH}_2\text{CH}_2$ halogen, and $-\text{CH}_2\text{CH}_2\text{OSO}_2\text{R}'$ radicals, and in which R' is phenyl.

4. Compounds having the formula:

in which R is selected from the group consisting of alkyl radicals having up to 10 carbon atoms, aralkyl radicals having up to 10 carbon atoms, cyclopentyl, cyclohexyl, $-\text{CH}_2\text{CH}_2$ halogen, and $-\text{CH}_2\text{CH}_2\text{OSO}_2\text{R}'$ radicals, and in which R' is benzyl.

5. Compounds having the formula:

in which R is selected from the group consisting of alkyl radicals having up to 10 carbon atoms, aralkyl radicals having up to 10 carbon atoms, cyclopentyl, cyclohexyl, $-\text{CH}_2\text{CH}_2$ halogen, and $-\text{CH}_2\text{CH}_2\text{OSO}_2\text{R}'$ radicals, and in which R' is tolyl.

6. A compound selected from the class consisting of 2,2'-di-mesyloxy-N-methyldiethylamine and its salts.

7. A compound selected from the class consisting of 2,2'-di-tosyloxy-N-cyclohexyldiethylamine and its salts.

8. A compound selected from the class consisting of 2,2'-di-(mesyloxy)-N-cyclohexyldiethylamine and its salts.

9. A compound selected from the class consisting of 2,2'-di-tosyloxy-N-benzylidethyldiethylamine and its salts.
